UNITED STATES PATENT OFFICE

MASON FOSHEE, OF JACKSONVILLE, FLORIDA

COLLAPSIBLE SHIPPING CRATE

Application filed April 12, 1932. Serial No. 604,816.

This invention relates to a collapsible metal bound wood veneer shipping crate for fruits, vegetables and the like, the general object of the invention being to provide a crate much less expensive than the crates now on the market, and of less weight than standard crates, which results in a saving of shipping charges, and which can be readily set up in the packing plant and without the expensive equipment now used in packing plants to assemble standard crates.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a side view of a crate constructed in accordance with this invention.

Fig. 2 is an end view thereof.

Fig. 3 is a longitudinal sectional view.

Fig. 4 is a fragmentary view of an inner side of one of the side members.

Fig. 5 is a perspective view of one of the end members.

Fig. 6 is a fragmentary view showing how the four side forming members are connected together by the bands.

In these drawings, the four sides of the crate are shown at A, B, C, and D, and each end piece at E. While the drawings show the side pieces formed of two slats each it will of course be understood that each side piece may be formed of a single strip or more than two strips and the drawings also show each end piece composed of four pieces arranged in pairs as shown in Fig. 5, but it will also be understood that these end pieces can be formed in any other desired manner.

In carrying out my invention, I connect the four side pieces A, B, C and D together by metal bands 1, any desired number of which can be used at each end of said side pieces, the drawings showing a pair of bands at each end and these bands may be connected

to the outside cleats 2 as shown or they may be connected directly to the side pieces.

Those portions of the bands between the individual strips forming the four side pieces should be of sufficient length to permit the side pieces to be folded upon each other to form a compact bundle. As shown in Fig. 6, the ends 2 of the bands 1 project from the adjacent strips and these projecting ends can be suitably fastened to the ends 3, such as for instance by a standard lap stapler.

When this is done, the body of the box is finished and it can be folded flat and bundled. Side cleats 4 are attached to the four side members at one end of the box and these cleats are of less length than the width of the side members as shown in Fig. 4 so as to not interfere with the folding of the side members. One of the end pieces or head E is placed against these cleats and then the box is filled after which the other end piece E or head is placed under a cleat similar to the cleat 4 which is fastened to the inside of one of the side members at the opposite end of the crate.

The other three cleats for this end of the box are shipped loose to the packer. After the said end or head E is placed under this single cleat the other cleats are put in place so that the articles in the crate or box will be held therein and the pressure of said articles will hold the end pieces or heads in position by pressing them against the cleats 4.

When a center head is used, four cleats similar to that shown at 4 in Fig. 4 are fastened to the four side members in the center of the crate to support the said center head and these cleats can also be put in place by the manufacturer. When the bulge pack is desired, the center bands 1' can be made longer on two corners than at the other corners so that the parts of one of the side members will bulge. Of course these center bands 1' can be used or not as desired. If used, they may be put in place by the manufacturer.

From the foregoing it will be seen that the four sides of the crate are connected together at the factory and in such a manner that they can be folded flat so as to form a flat bundle when shipped to the packing house. The two

ends and the center piece, if used, also packs flat and the three loose cleats can be put in place by the packer after the crate has been packed to hold the top end in position.

5 Then when the shipper receives the parts, he simply opens the package forming the four sides inserts one of the ends so that it will rest against the cleats 4 at one end of the body and then packs the fruit and then places 10 the other end under the single cleat at the opposite end of the body and then fastens the other three cleats in position.

It will of course be understood that if desired, but two cleats can be used for holding 15 each end in position and that instead of using continuous bands as shown in Fig. 6, short strips can be used to fasten the individual pieces together.

With this invention wood veneer materials 20 can be used from one-eighth to one-fourth inch in thickness.

It is thought from the foregoing description that the advantages and novel features 25 of the invention will be readily apparent.

25 It is to be understood that changes may be made in the construction and in the combination and arrangement of the several parts provided that such changes fall within the scope of the appended claims.

30 Having thus described my invention, what I claim as new is:—

1. A crate of the class described comprising four side members formed of longitudinally extending thin strips and transversely 35 extending exterior cleats, one member forming the top of the crate, another the bottom thereof and the remaining ones the sides of the crate, metallic bands of flexible material passing transversely around the crate and 40 connecting the members together in spaced relation, each band having its ends permanently connected together, those portions of the bands between the members being of sufficient length to permit the members to be folded 45 flat with the top member on one side member and the other side member on the bottom member, a pair of end members and cleats fastened to the inner faces of the side members adjacent the ends thereof for holding the end 50 members in place.

2. A crate of the class described comprising four side members formed of longitudinally extending thin strips and transversely extending exterior cleats, one member forming the 55 top of the crate, another the bottom thereof and the remaining ones the sides of the crate, metallic bands of flexible material passing transversely around the crate and connecting the members together in spaced relation, 60 each band having its ends permanently connected together, those portions of the bands between the members being of sufficient length to permit the members to be folded flat with the top member on one side member and the other side member on the bottom 65

member, a transverse cleat on the inner side of each member adjacent an end thereof, a pair of end members, one of which engages the inner edges of the inner cleats when the end member is placed in the crate after the side members have been moved to a position to form a rectangular body and cleats for holding the second end member in place.

In testimony whereof I affix my signature. 70
